UNITED STATES PATENT OFFICE.

ERNEST CHARLES FASOLDT, OF ALBANY, NEW YORK, ASSIGNOR OF TWO-THIRDS TO
LOUIS R. KRUG, OF ALBANY, NEW YORK.

RHEOSTAT.

Application filed April 7, 1922. Serial No. 550,370.

To all whom it may concern:

Be it known that I, ERNEST C. FASOLDT, a citizen of the United States, and a resident of Albany, in the county of Albany 5 and State of New York, have invented a new and Improved Rheostat, of which the following is a full, clear, and exact description.

This invention relates to improvements in 10 rheostats, an object of the invention being to provide a rheostat capable of micrometer adjustment.

A further object is to provide a rheostat capable of such delicate adjustment that the same may be used as a potentiometer, and a rheostat which provides for a micro-ampere flow of current, such as is used in a vacuum tube for the reception of a telegraph, or with other apparatus, as in wireless or radio 20 receiving outfits.

A stiff further object is to provide a device of this character, which will be simple and practical in construction, efficient in use, and which will lend itself to economical manufacture.

With these and other objects in view, the invention consists in certain novel features of construction, and combinations and arrangements of parts as will be more fully 30 hereinafter described and pointed out in the claims.

In the accompanying drawings:—

Figure 1 is a top plan view of my improved rheostat; and

Figure 2 is a transverse sectional view therethrough on the staggered line 2—2 of Figure 1.

Referring in detail to the drawings, I have used the reference numeral 1 to designate the body portion of my improved rheostat, which is formed of some insulating material and provided with an integral flanged base 2. Binding posts 3 and 4 are mounted at diametrically opposed points 40 upon the base for the attachment of electric wires 5 and 6 respectively. The body 1 includes a hollow center accommodating an internally screw threaded brass sleeve 7, in which a hollow screw 8 is movable.

The body 1 is externally threaded, as indicated at 9, the external threads of the base and the internal threads of the sleeve being similarly pitched. Resistance wire 10 is wrapped in the external threads of the

body 1 and suitably connected to the binding post 4, as indicated at 11. The screw 8 terminates in an upwardly presented shank 12, upon which an insulated cap or handle 13 is secured by a nut 14 screwed onto the upper end of the post and located in a recess 15 in the top of the cap.

The reduced upper end or shank of the screw 8 provides a shoulder 16 on the screw which supports a circular metallic plate 17 slipped over the shank and held against the shoulder by the cap 13. The plate 17 carries at spaced intervals depending spring fingers 18 contacting with the wire of the resistance coil. I preferably utilize three or four of these fingers. Contact between the binding post 3 and the screw 8 is established by an arm 19 connected to the binding post and extending below the base 2 and sleeve 7, which serves to support a coiled expansion spring 20 extending upwardly into the hollow screw 8 and making contact between the screw and the arm.

When the device is in operation, current passes from the wire 5 through the post 3, arm 19, spring 20, sleeve 7, plate 17 and 80 fingers 18, to the resistance coil, from whence it flows to the other binding post 4 and wire 6. Any desired amount of resistance may be thrown out or in by simply turning the cap or handle 13 to raise or 85 lower the screw 8, and consequently, the fingers 18 which contact with the resistance wire. By virtue of this screw threaded adjustment it will be seen that an exceedingly delicate instrument is provided and that 90 any desired amount of resistance may be thrown in or out.

I have illustrated one of the preferred embodiments of my invention, but numerous slight changes and alterations might be 95 made in the general form and arrangement of the parts described, without departing from the invention, and hence I do not wish to limit myself to the precise details set forth, but shall consider myself at liberty to make such slight changes and alterations as fairly fall within the spirit and scope of the appended claims.

I claim:

1. In a rheostat, a body of insulating material, a resistance coil spirally wound around the body, an internally threaded sleeve in the body, a screw movable in the

sleeve, a plate fixed to turn with the screw, spring fingers integral with the plate contacting with the coil to delicately regulate current flow, and a handle of insulating material resting on the plate and secured to the screw for turning the same.

2. In a rheostat, a body of insulating material, a resistance coil spirally wound around the body, an internally threaded sleeve in the body, a screw screwing into the sleeve and having a reduced shank, a plate having an opening through which the shank of the screw extends and provided with spring fingers engaging the said coil, and
- 10 a handle of insulating material on the shank of the screw, and means for securing the handle on the shank and the plate to the screw.
3. In a rheostat, a body of insulating material, including a flanged base, binding posts on the base, a resistance coil spirally wound about the body and directly connected to one post, an internally screw threaded sleeve in the body, a screw movable in the sleeve, an inwardly extending arm fixed to the other binding post, a coiled conductive expansion spring interposed between the arm and screw, means carried by the screw held in contact with the coil by its own resiliency, and means for turning the screw to regulate through said means the amount of resistance in the current.
- 20
4. In a rheostat, a body of insulating material and having a flanged base, binding posts on the base, a resistance coil wound upon the body and connected with one binding post, an internally threaded sleeve in the body, a hollow screw screwing into the sleeve, a plate secured upon the screw and having spring fingers engaging the resistance coil, a plate secured to the other binding post and extending under its sleeve, a spring engaging the said plate and extending into the hollow screw, and a handle for turning the screw.
- 25
5. In a rheostat, a body of insulating material and having a flanged base, binding posts on the base, a resistance coil wound upon the body and connected with one binding post, an internally threaded sleeve in the body, a hollow screw screwing into the sleeve, a plate secured upon the screw and having spring fingers engaging the resistance coil, a plate secured to the other binding post and extending under its sleeve, a spring engaging the said plate and extending into the hollow screw, and a handle for turning the screw.
- 30

ERNEST CHARLES FASOLDT.
